UNITED STATES PATENT OFFICE.

FREDRICK C. MILLER AND HENRY C. PETERS, OF NEW YORK, N. Y.

CIGAR-MOLD.

SPECIFICATION forming part of Letters Patent No. 244,914, dated July 26, 1881.

Application filed January 25, 1881. (No model.)

To all whom it may concern:

Be it known that we, FREDRICK C. MILLER and HENRY C. PETERS, both citizens of the United States, residents of New York, in the county of New York and State of New York, have invented certain new and useful Improvements in Cigar-Molds, of which the following is a specification.

Our invention relates to certain improvements in cigar-molds; and it consists in combining with the base of a cigar-mold and the dowel pin or pins thereof a lid carrying the plungers, said lid being provided with one or more openings for the dowel-pin at either or both ends, said openings being elongated or enlarged at their lower portion, or the described equivalent construction thereof, for enabling the plunger to be moved out of the matrix without subjecting the edges of the plungers or division-walls of the matrices to strain or pressure sufficient to break or injure the same.

The object of our invention is to prevent the breaking off of the ends of the plungers or splitting off of the edges of the cups in the act of opening, which is a very common occurrence with the ordinary kind of molds, which, although adapted to be opened by the use of wedges inserted in gains at each end, cannot practically be so used, as the operator cannot conveniently insert the wedges simultaneously at each end, and consequently one end is nearly always opened first, which results in injury to the cup or plunger.

Another advantage of our invention is that it allows the molds to be opened at one end only by the use of but one wedge without any danger of injury to the cups.

In the drawings, Figure 1 is a broken longitudinal section through the center of the lid of the mold with the dowel-hole enlarged at its lower portion in order to allow the raising of the lid from one end only. Fig. 2 is a central section, showing our improvements in the preferred form. Fig. 3 is a broken side elevation, showing a modified form of mold. Fig. 4 is an end elevation of a mold, showing a modification of our improvements. Fig. 5 is a top view of a portion of the lid, and shows a modified form of opening for the dowel-pin.

50 A indicates the base of the mold; A' A''', sectional parts rigidly attached to the base

A, which together form the lower or matrix portion of the mold, the parts A' A''' being end blocks interposed between the base A and the lid B, and the parts A'' being the blocks 55 in which the matrices are formed.

B indicates the lid, and B' the plungers, rigidly attached to it in the ordinary manner.

a indicates the dowel-pin, and b a hole pierced in the lid for receiving it. A similar 60 dowel-pin may be used in the opposite end of the mold.

In the preferred form, as shown in Fig. 2, the mold continues out beyond the end matrix to the point x, which becomes the center or 65 pivotal point on which the lid bears when the opposite end is raised. As illustrated in said figure, this extension of the mold is made by extending the base A, the lid B, and the interposed block A' some distance beyond the 70 matrix that is at such end of the mold, the dowel-pin being secured in the base and block adjacent to said end matrix.

It will be obvious that when the lid is raised the point x of contact between the lid and the 75 block A' at the outer extremities of said parts will constitute the pivot upon which the lid turns when it is raised. If such point were near the matrices, as in the case of other cigar-molds of this character, the paths described 80 by the plungers, and more especially those nearest to the said end of the mold, would be small circles; but by lengthening or extending the lid, the base, and the block A', it will be seen that said paths, in which the plungers 85 move when the lid is raised, will be circles so large that the plungers will rise in nearly perpendicular planes.

The part A' is shown as being a block separate from the matrices and the base; but it 90 is obvious that the same results will be obtained if said block or piece A' be integral with the lid or the matrices, or the base upon which the matrices are arranged.

It may be desirable in some instances to 95 have the mold made so that either end may be opened, in which case the mold would be made as shown in Fig. 3, D being the gain for the insertion of the wedge, and the point x being preserved by the extension of the parts A' B 100 of the mold beyond the gain D, as shown.

x', Fig. 3, shows the path of the plunger B'

when the point x is the center, which, it will be seen, is in line nearly parallel with the sides of the matrix A'', which the plungers B' enter. To allow the plunger B' to rise in a line parallel with the sides of the matrices, the dowel-hole b in the lid B is gradually enlarged from its upper to its lower end by cutting away the lid at the inner side of the hole, as shown by the full line b' , Figs. 1 and 2, and the dotted line a^2 , Fig. 3. Instead of enlarging this opening, as shown in Figs. 1 and 2, in which the lower portion of the same is larger than its upper portion, said opening can be made oblong, as shown in Fig. 5, the diameter of the opening in such instance being the same at the top as at the bottom part thereof; or, instead of enlarging the opening, the same result can be obtained by beveling or flattening one side of the dowel-pin, as indicated at a' , Fig. 2, and shown by dotted lines, Fig. 3. In this way when the lid is raised at one end so that the pivot on which the lid turns will be at the point x at the outer extremities of the block A' and the lid B, that portion of the lid forming that side of the side of the opening b that is nearest to the matrices will clear the dowel-pin, so as not to interfere with the raising of the lid.

In a modification we construct either end of the mold and dowels, as shown at the left-hand side of Fig. 3, with the gain cut in at the end. The opening in the lid, of which there may be one or more at each end, is shown in full lines, Figs. 1 and 2, as being enlarged at its lower end for the purpose of receiving the pointed or beveled dowel pin or pins of the mold, and by the employment of the openings thus formed the plungers can with safety be moved out from the matrices or separated therefrom without subjecting the longitudinal edges of the plungers or division-walls of the matrices to undue strain or pressure, and thereby there will be no liability of breaking or injuring the edges or walls. The lid may be made to carry the dowel pin or pins, and the opening or openings be made in the base of the mold, if desired, without departure from our invention.

Our improvement is a very important one,

as it allows the mold to be opened at one end without any danger of injury to the plungers, 50 and also allows a closer fit of the cups in the matrix than could be obtained in the old form of construction.

In Fig. 4 the gain E is formed in the end of the mold, between the sides, so that the extended ends are preserved for the purpose already set forth. 55

C indicates an elastic band surrounding the plunger. This forms the subject of a separate 60 application.

In this application is shown and described a cigar-mold composed of a base supporting a series of matrices, with extension or end pieces between the base and lid, said lid carrying a series of plungers, and provided near one end 65 with an opening for the entrance of a pointed dowel-pin, which is additionally beveled or flattened to secure the results named herein, a rabbet being formed in the mold at the end opposite the dowel-pin for the insertion of a wedge to enable the lid to be separated from the base; but as such organization will be the subject-matter of another application for patent, the same is not claimed herein.

What we claim is—
In combination with the base of a cigar-mold and the dowel pin or pins thereof, a lid carrying the plungers provided with one or more openings at either or both ends for passage of the dowel pin or pins, said opening or openings being elongated or enlarged at their lower portion, or the described equivalent construction thereof, for enabling the plunger to be moved out of the matrix without subjecting the edges of the plungers or division-walls 85 of the matrices to strain or pressure sufficient to break or injure the same, substantially as described.

In testimony whereof we have hereunto set our hands in the presence of two subscribing 90 witnesses.

FREDRICK C. MILLER.
HENRY C. PETERS.
